[57] **CLAIM**

The design for a cushion device for swimming pool ladder device, as shown and described.

DESCRIPTION

FIG. 1 is an environmental view of a cushion device for swimming pool ladder showing our new design, with phantom lines shown for illustrative purposes only and form no part of the claimed design;

FIG. 2 is an isometric view thereof;

FIG. 3 is a front view thereof;

FIG. 4 is a top plan view thereof;

FIG. 5 is a rear view thereof;

FIG. 6 is an end view thereof; and,

FIG. 7 is a cross-sectional view taken along line 7—7 of FIG. 3.
